UNITED STATES PATENT OFFICE.

VICTOR R. DESPARD AND HANS C. R. POPP, OF VALPARAISO, INDIANA, ASSIGNEES TO
MCGILL MANUFACTURING COMPANY, A CORPORATION OF INDIANA.

SWITCH-OPERATING MEANS.

Application filed June 3, 1927. Serial No. 196,261.

Our invention relates to operating means for switches and more particularly to means for causing step by step rotation of a rotary switch, always in the same direction.

- 5 It is a purpose of this invention to provide a simple operating means which may be actuated by a pull chain or cord and which will not be impaired by an excessive pull on the pull chain.
- 10 It is also an object of the invention to provide a novel means for mounting the operating structure upon the rotary stem of the switch.

15 A further object of this invention is to simplify the connection between the actuating member and the stem of the switch by the provision of a novel spring and ratchet wheel structure.

20 Other objects and advantages of the invention will appear as the description proceeds in connection with the accompanying drawings. However we wish it to be understood that we do not intend to limit ourselves to the exact details shown but that 25 we intend to avail ourselves of all such modifications as would occur to one skilled in this art and as fall within the scope of the claims.

In the drawings:

30 Fig. 1 is a side view showing the switch operating mechanism;

Fig. 2 is a side view at right angles to Fig. 1;

35 Fig. 3 is a horizontal section taken centrally through the switch and the operating mechanism; and

Fig. 4 is a detailed view of the switch operating mechanism in the extreme opposite position to that shown in Fig. 1.

40 Referring now in detail to the drawings, the numeral 10 indicates generally the switch body which is preferably formed of insulating material and has a recess 11 therein which recess is provided with the shouldered portion at 12 upon which stationary contacts, one of which is indicated at 13, rest. These stationary contacts may be connected in any suitable manner to conductors, such for instance as in the manner shown in 45 the application of Victor Despard Serial No. 62,833 now Patent No. 1,669,372 issued May 8, 1928, filed October 16, 1925 on multiple series switch. Seated within the recess 11 is the insulating disc 14 having mov-

able contact members, one of which is illustrated at 15, mounted thereon, the disc 14 being rotated by means of the stem 16 which extends into the member 14 through an insulating disc 17 held in place by means of the spring 18 surrounding the stem 16. The recess 11 is covered by means of the insulating plate 19 and the metal finishing plate 20 which is secured to the base portion 10 by means of the screws shown at 21 and 22.

55 It will be noted that the plate 20 is pressed outwardly as at 24 to provide a seat for the enlarged portion 25 on the stem 16 and is provided with an opening substantially centrally of the projecting portion 24 through which the outer end 26 of the stem 60 16 extends. This outer end as shown is provided with a pair of projections 27 and 28 for a purpose which will presently appear.

65 The actuating mechanism for causing step by step rotation of the member 16 comprises the ratchet wheel or disc 30 having a pair of openings therein receiving the prongs 70 27 and 28 which are then bent toward each other as shown in Fig. 3 to secure the ratchet wheel to the stem. Pivoted on the stem 75 between the ratchet wheel and the projection 24 is the member 31 which as shown has a projection 32 extending outwardly beyond the ratchet wheel at one side thereof 80 and substantially opposite this projection is provided the downturned portion 33 having the curved projection 34 thereon slotted as at 35 to receive the chain 36 consisting of a 85 plurality of balls and links connecting them. 90

95 A coiled spring 38 surrounds the projection 34 and has a hooked portion 39 engaging the stop 40 struck up from the plate 20, the other end of the coiled spring being bent in front of the projection 32 and having the end 41 thereof hooked over the ratchet wheel 30. This spring is placed in position under tension so that in the position shown at Fig. 1 the tendency of the 100 spring is to maintain the member 31 in the position shown in Fig. 1 where the projection 32 engages the stop 40 to limit movement of the member 31 in one direction. Now when the member 31 is rotated by means of the chain 36, the hook portion 41 105 of the spring 38 will be carried by the member 32 into engagement with one of the teeth of the ratchet wheel and thus move the

ratchet wheel and the stem 16 with it from the position shown in Fig. 1 to that shown in Fig. 4 and slightly beyond this position so that the projection 33 also engages the stop 40. Upon release of the tension on the chain 36, the end 41 of the spring will force the member 31 back into the position shown in Fig. 1, the spring during this movement simply riding over the rounded portions of the ratchet teeth without causing any rotation of the ratchet wheel.

Thus the spring in this construction serves a dual purpose in that it returns the pivot member 31 back to starting position upon release of the pull chain, and, during the movement of the member 31 under the influence of the pull chain, it connects the projection 32 to the ratchet wheel 30 so as to cause rotation of the ratchet wheel without the interposition of any other structure. The single limiting stop 40 struck up from the plate 20 serves to limit the rotating movement of the member 31 in both directions and at the same time holds the end 39 of the spring 38 in position. This makes an exceedingly simple structure which is cheap to manufacture and has few parts to get out of order so that it will last indefinitely. The spring itself is protected by means of the stop 40 and the projections 32 and 33 from any undue strain due to an excessive pull on the pull chain 36.

From the above description it is thought that the construction and operation of this device will be clear to those skilled in this art and having thus described our invention what we claim and desire to secure by Letters Patent of the United States is:

1. Switch operating mechanism for rotary switches comprising a rotatable stem, a ratchet member thereon, a coiled spring encircling said stem and having one end fixed relative to the switch casing, said spring having a portion adjacent the other end thereof connected with the teeth of said ratchet member whereby movement of said portion in one direction causes rotation of said ratchet member and movement in the opposite direction causes said portion to slide relative to said ratchet member, and actuating means for moving said portion in the first named direction, said spring serving to return said portion to normal position upon release of said actuating means.
2. Switch operating mechanism for rotary switches comprising a rotatable stem, a ratchet wheel fixed thereon, a coiled spring surrounding said stem having one end connected to the switch casing and the other end hooked over the rim of the ratchet wheel so as to engage the teeth thereon, and means engaging said spring at its hooked end for causing rotative movement of said hooked end and thereby said ratchet wheel in one direction against the force of the spring.

3. Switch operating mechanism for rotary switches comprising a rotatable stem, a ratchet wheel fixed thereon, a coiled spring surrounding said stem having one end connected to the switch casing and the other end hooked over the rim of the ratchet wheel so as to engage the teeth thereon, and means engaging said spring at its hooked end for causing rotative movement of said hooked end and thereby said ratchet wheel in one direction against the force of the spring, said means including a member rockable about the axis of said stem.

4. Switch operating mechanism for rotary switches comprising a rotatable stem, a ratchet wheel fixed thereon, a coiled spring surrounding said stem having one end connected to the switch casing and the other end hooked over the rim of the ratchet wheel so as to engage the teeth thereon, and means engaging said spring at its hooked end for causing rotative movement of said hooked end and thereby said ratchet wheel in one direction against the force of the spring, said means comprising an actuating member pivoted on said stem and having a projection thereon engaging the spring adjacent its hooked end.

5. Switch operating mechanism for rotary switches comprising a rotatable stem, a ratchet wheel fixed thereon, a coiled spring surrounding said stem having one end connected to the switch casing and the other end hooked over the rim of the ratchet wheel so as to engage the teeth thereon, and means engaging said spring at its hooked end for causing rotative movement of said hooked end and thereby said ratchet wheel in one direction against the force of the spring, said means including a member rockable about the axis of said stem, and stop means for limiting the rocking movement of said member in both directions.

6. Switch operating mechanism for rotary switches comprising a rotatable stem, a ratchet wheel fixed thereon, a coiled spring surrounding said stem having one end connected to the switch casing and the other end hooked over the rim of the ratchet wheel so as to engage the teeth thereon, and means engaging said spring at its hooked end for causing rotative movement of said hooked end and thereby said ratchet wheel in one direction against the force of the spring, said means including a member rockable about the axis of said stem, and stop means for limiting the rocking movement of said member in both directions, said stop means also connecting said spring to the switch casing.

7. Switch operating mechanism for rotary switches comprising a rotatable stem, a ratchet member thereon, a coiled spring encircling said stem and having one end fixed relative to the switch casing, said spring having a portion adjacent the other end

- thereof connected with the teeth of said ratchet member whereby movement of said portion in one direction causes rotation of said ratchet member and movement in the 5 opposite direction causes said portion to slide relative to said ratchet member, and actuating means for moving said portion in the first named direction, said spring serving to return said portion to normal position 10 upon release of said actuating means, and stop means on the switch casing cooperating with said actuating means for limiting the rotation of said portion in both directions.
8. Switch operating mechanism for rotary 15 switches comprising a rotatable stem projecting from the switch casing and having spaced projections at the end thereof, a ratchet wheel having openings receiving said projections, said projections being bent over 20 to lock the ratchet wheel in place, and means including a spring surrounding said

stem for causing step by step rotation of said ratchet wheel and stem.

9. Switch operating mechanism for rotary switches comprising a rotatable stem 25 projecting from the switch casing, a ratchet wheel fixed to said stem, a projection on said casing, a coiled spring surrounding said stem and having one end secured to said projection, the other end of said spring engaging 30 the teeth of said ratchet wheel, and an actuating member pivoted about said stem and engaging said spring for causing rotation of said ratchet wheel and means on said actuating member adapted to engage said 35 projection to limit the rotation of said actuating member in both directions.

In witness whereof, we hereunto subscribe our names this 16th day of May, A. D. 1927.

VICTOR R. DESPARD.
HANS C. R. POPP.
